(57) **CLAIM**

The ornamental design for a “multi-functional adapter”, as shown and described.

DESCRIPTION

FIG. 1 is a front perspective view of a multi-functional adapter showing my new design;
FIG. 2 is another front perspective view of the design of FIG. 1, rotated by 180 degrees;
FIG. 3 is a front view of the design of FIG. 1;
FIG. 4 is a rear view of the design of FIG. 1;
FIG. 5 is a left side view of the design of FIG. 1;
FIG. 6 is a right side view of the design of FIG. 1;
FIG. 7 is a top view of the design of FIG. 1; and,
FIG. 8 is a bottom view of the design of FIG. 1.
The broken lines in the figures depict portions of the multi-functional adapter that form no part of the claimed design.
